ADJUSTABLE CHAIR

Roy A. Cramer, Kansas City, Mo.

Application March 29, 1946, Serial No. 658,276

11 Claims. (Cl. 155—115)

1 This invention relates to chairs and more particularly to improvements in chairs of the posture type adapted for office use, although it will be understood that the improvements may be advantageously employed in chairs adapted for other uses.

Posture chairs of the general type to which this invention relates have heretofore been provided with various types of adjustments in order that the positions of the seat and back rest may be readily varied to secure a comfortable and proper posture position for the particular user of the chair. For example, the back rest has been so arranged as to be tiltable as well as adjustable vertically and horizontally with respect to the seat in an effort to arrange the back rest in a proper position. In making such adjustments in the prior chairs, the back rest support was first adjusted horizontally and vertically with respect to the seats after which the support for the back rest was locked in position. With such an arrangement, it has been found that even with the back rest arranged for tilting movement about a horizontal pivot, the user's back was subjected to a considerable amount of "back rub" as he leaned back in the chair a repeated number of times. This operation caused the user's garment, which was in contact with the back rest, to be stretched upwardly and subjected his back to an uncomfortable rubbing action.

In the prior chairs, it was also determined that when the back rest support was adjusted to move the back rest rearwardly of the seat, the weight distribution of the user of the chair was such that the chair was unstable with respect to its support. For example, in such case, the center of gravity of the user of the chair would be shifted to the rear of the center of support of the chair seat and the chair would have a tendency to tilt backwardly. This resulted in an undesirable unstable condition.

It is accordingly one of the objects of the present invention to provide a posture chair which is so constituted as to avoid the disadvantages and objectionable features now present in chairs of this type.

Another object is to provide a novel posture chair construction which is provided with a back rest so constructed as to entirely eliminate "back rub" when the chair is in use.

Still another object is to provide a novel back rest construction in a chair of the above type, which is so arranged as to be automatically tiltable about a horizontal axis above the seat, and also arranged to be automatically adjustable ver-

tically of the seat, these combined adjustments being automatically effected by the back of the user and resulting in the complete elimination of "back rub."

5 A further object includes the provision of a floating back rest for a chair of the above character which automatically accommodates itself to the user's back, thus securing an exceedingly comfortable back support without "back rub."

10 Still another object comprehends a posture chair construction wherein, with the chair in use, a proper weight distribution is maintained at all times, regardless of the adjustment of the back rest and support therefor, toward or away from the seat, such an arrangement maintaining a high degree of stability of the chair under all conditions of adjustment.

15 Another object resides in the provision of a novel arrangement for interconnecting the back rest support, seat and seat support, in such a manner that as the back rest support is adjusted toward the seat, the latter automatically moves rearwardly with respect to the seat support and toward the back rest support, and as the back rest support is adjusted away from the seat to accommodate a person of larger size, the seat automatically moves forwardly with respect to the seat support and away from the back support, this construction being such as to automatically position the center of gravity of the user of the chair substantially over the center of support for the seat, regardless of the size of the person using the chair.

20 A further object includes a novel chair construction embodying the foregoing highly desirable and advantageous results which includes the adjustments heretofore stated and which function to fully and comfortably compensate the chair to persons of various sizes, the structure embodying relatively few parts and thus being capable of being economically manufactured.

25 Other objects and novel features of the invention will appear more fully hereinafter, from a consideration of the following detailed description when taken in connection with the accompanying drawings wherein the invention is illustrated. It is to be expressly understood, however, that the drawings are utilized for purposes of illustration only, and are not designed as a definition of the limits of the invention, reference being had for this latter purpose to the appended claims.

30 In the drawings, wherein similar reference characters refer to similar parts throughout the several views:

Fig. 1 is a side view of a chair constructed in accordance with the principles of the present invention and illustrating in dotted lines, the various adjustments of the back rest, the back rest support and the seat;

Fig. 2 is a plan view of the under side of the seat of the chair shown in Fig. 1;

Fig. 3 is a partial sectional view taken along line 3—3 of Fig. 2;

Fig. 4 is a fragmentary perspective view of a part of the seat spider and bracket for the back rest support;

Fig. 5 is a vertical sectional view of the back rest and illustrates the construction for securing the combined automatic tilting and the vertical movement of the back rest;

Fig. 6 is a front view of the back rest construction with the back rest cushion and supporting plate removed;

Fig. 7 is a partial sectional view taken along line 7—7 of Fig. 6 and illustrates one of the guides for securing the automatic vertical movement of the back rest, and

Fig. 8 is a perspective view of a modified form of back rest support which may be employed.

Referring more particularly to Fig. 1, a novel chair construction embodying the principles of the present invention is illustrated therein as including a base 10 adapted to support a seat 12 by means of a pedestal 14, the latter being adjustable in the base in any suitable manner in order to adjust the height of the seat. A back rest 16 is adjustably secured to the upper portion of a back rest support 18, the latter being preferably formed of metal having some yieldability and being bent into an L-shaped form having an arm 20 which is adjustably carried beneath the seat 12 in a manner which will appear more fully hereinafter. As shown, the seat 12 and the back rest 16 are provided with cushions, preferably of the latex foam type, and these are provided with suitable covers which are maintained in position by any convenient arrangement.

One of the features of the present invention resides in the provision of a novel construction for maintaining the stability of the chair, irrespective of the adjustment of the back rest support 18 to accommodate the chair to different size persons. In the form of the invention illustrated, such feature comprises an arrangement which is operative to automatically shift the position of the seat 12 with respect to the pedestal 14, as the back rest support 18 is moved in a direction toward and away from the seat. More particularly, and referring to Fig. 1, the full line position of the support 18 and the seat 12 is such that the former is closely adjacent the rear edge of the latter, and the center of the seat 12 as shown at 22, is slightly to the rear of the center line 24 of the pedestal 14. It has been determined, that in the majority of cases when the parts are arranged in this manner, the center of gravity of the user of the chair, will substantially coincide with the center line 24 of the pedestal, in which event, the chair is perfectly stabilized when in use.

In the event however, that a deeper seat is found to be desirable, and the support 18 is moved rearwardly toward the dotted line position, the present invention includes an arrangement for moving the seat 12 forwardly with respect to the pedestal 14 toward the dotted line position shown in Fig. 1. It will thus be clear that in such position, while the center 22 of the seat 12 is positioned forwardly of the center line 24 of the pedestal, as

shown in dotted lines, still the center of gravity of the user, will substantially coincide with the center 24 of the pedestal 14. In this manner, it will be appreciated that the stability of the chair under various positions of adjustment, will be materially increased.

Referring now to Fig. 2, in addition to Fig. 1, the foregoing novel construction includes an arrangement for interconnecting the arm 20 of the support 18, the seat 12 and the pedestal 14 in order to secure the advantageous results referred to above. More particularly, a seat spider 26 is secured to the upper end of the pedestal 14, and is provided with a plurality of outwardly extending arms 28, 30, 32 and 34, all of which may be arranged in a substantially horizontal plane. The seat 14 includes a metal seat plate 36 which is provided on its under side with a pair of ribs 38 and 40 which are parallel to each other and which are capped with flat plates 42 and 44. This construction thus provides a pair of guides or tracks for receiving the ends of the arms 28, 30, 32 and 34 so that the seat plate 36 and the seat 14 are capable of substantially horizontal movement, fore and aft of the spider 26. In order to support the arm 20 of the back rest support 18, the seat plate is provided with a block 46 which includes a pair of ways 48, 50 on which the arm 20 is adapted to slide. A suitable set screw 52, provided with a hand wheel 54 is threaded received by a portion of the spider 26 in order to secure the arm 20 in any desired position of adjustment along the ways 48, 50.

In order to provide the above-mentioned combined adjustment of the back rest support and seat, the spider 26 includes a projecting arm 56 which carries a pivot pin 58 adapted to engage a lever 60 intermediate the ends of the latter. As shown, the outer end of the lever 60 is slotted at 62 and receives a stud or screw 64 which is secured to the seat plate 36. The inner end of the lever 60 on the other hand, may be slotted at 66 for the reception of a stud or screw 68 carried by the arm 20. Preferably, the spider 26 is slotted at 70 to accommodate the inner end of the lever 60 which is positioned between the spider and the block 46. With such an arrangement it will be understood that in the full line position of the back rest support as shown at 18a, and the full line position of the seat, as indicated at 12a, the lever 60 will occupy the position denoted by the arrow 1. On the other hand, should the back rest support 18 be moved toward the seat 12, as viewed in Fig. 2 to the position 18b, the lever 60 will rotate in a counter-clockwise direction about the fixed pivot 58 to a position indicated by the arrow 2 and cause the seat to be moved rearwardly to the position 12b. Also, should the support 18 be moved away from the seat to the position 18c, the lever 60 will pivot to a position indicated by the arrow 3 while the seat will move forwardly and finally reach the position shown at 12c. Thus with such a construction, it will be seen that the back rest support 18 and the seat 12 are moved in opposite directions when it is desired to adjust the chair for different size persons. The adjustments are such, however, that the center of gravity of the user of the chair will, at all times, substantially coincide with the center line of the pedestal 14 and hence the stability of the chair will be maintained under all conditions.

A further feature of the invention resides in a floating back rest construction which is so arranged as to eliminate "back rub" when the chair 75 is in use. Referring more particularly to Figs. 1,

5 and 6, the foregoing desirable result is achieved by mounting the back rest 16 on the upper end portion of the support 18 in such a manner that the back rest may not only tilt or pivot about a horizontal axis, but may also move in a substantially vertical plane. Thus, when the chair is in use and pressure is exerted against the back rest to flex the support 18, the back rest will automatically shift with the back of the user, thereby eliminating the uncomfortable "back rub" inherent in the prior types of posture chairs.

More particularly, and referring to Figs. 1, 5 and 6, a hollow sleeve 72 is adjustably secured as by means of a hand screw 14 to the support 18, and is provided at its upper portion with a pair of flanges 76 and 78 for mounting the back rest 16. The latter includes a hollow box 80 to which a cushion supporting plate 82 is secured through screws 84, it being pointed out that a second plate 86 which carries the back rest cushion and cover, is attached to the plate 82 by means of a pair of screws having thumb nuts 88, see Fig. 1.

For the purpose of interconnecting the sleeve 72 and box 80, the latter carries a pivot shaft or pin 90 which extends through slots 92 and 94 formed in the respective flanges 76 and 78. A strap 96 is associated with the central portion of the pin 90 and is provided with a pair of seats 98, 100 for respectively maintaining springs 102 and 104 in the position illustrated. These springs, when assembled, are placed under a slight initial tension, and in the normal position of the parts, serve to maintain the back rest in a substantially vertical position. It will be clear, however, that in use, the back rest may tilt or rock about the axis of the pin 90, and thus accommodate itself, to the inclination of the user's back.

In view of the mounting of the pivot pin 90 in the slots 92 and 94 of the sleeve 72, it will be readily understood that the back rest 16 may be moved in a substantially vertical plane. While the slots may if desired, be used to guide the pin 90, it is preferred to utilize roller bearing assemblies 106 and 108 which are carried by the pin 90 and which travel in tracks or guides 110 and 112 formed in the respective flanges 76 and 78 during movement of the back rest 16 with respect to the support 18. Normally, the pin 90 and back rest 16 are maintained in the position illustrated, as by means of a pair of springs 114 and 116 which are interposed between the pin 90 and a plate 118. Telescoping parts 120 and 122, respectively carried by the pin 90 and a bracket 124 formed on or carried by the sleeve 72, constitute guides for the springs, it being understood that this construction serves to maintain the springs in the vertical position illustrated. From the foregoing it is seen that the back rest 16 is yieldingly mounted for vertical movement with respect to the support 18 and that during such movement the mechanism permitting tilting movement of the back rest and including the strap 96 and springs 102 and 104 moves with the back rest. Thus with the chair in use, the back rest automatically tilts or rocks about the axis of pin 90 and at the same time, shifts in a vertical direction in order to accommodate itself to the position of the back of the user, and thereby eliminates all "back rub."

Means are preferably provided by the present invention to adjust the tension of the springs 114 and 116 in order to vary the force required to shift the back rest downwardly. In the form of the invention illustrated, such means includes an adjusting screw 126 which projects through a

threaded opening 128 in the bracket 124 and is attached to the plate 118. If desired, a lock nut, may be employed to lock the screw 126 in any desired position of adjustment.

A slightly modified form of back rest support is illustrated at 130 in Fig. 8, this being identical with the support 18 previously described, except for the provision of a plurality of slots or elongated openings 132 in the arm 134 which fits beneath the seat 12. In using this form of back rest support, the inner end of the lever 60 may be provided with a screw which projects into and cooperates with one of the openings 132, it being understood that by providing a plurality of such openings, the initial position of the back rest support with respect to the seat may be adjusted before the support, seat and seat spider are interconnected. The same initial adjustment may be secured with the support 18, by providing the inner end of the arm 20 thereof, with a series of spaced apart threaded openings for receiving the screw 68.

Referring to Fig. 3, it will be seen that the seat plate 36 is provided with an annular groove 136 adapted to receive a rubber bumper 138, it being understood that prior to placing the bumper in position, the edge of the cover 140 for the seat cushion is placed within the groove 136 and drawn tightly therein by tensioning and securing the ends 142 and 144 of a wire which is received within the hem of the cover. After the cover has been assembled as above described, the bumper 138 is placed within the groove 136, the resulting construction presenting a neat and attractive appearance as well as providing an efficient yieldable bumper guard for the chair seat.

Certain subject matter disclosed herein is claimed in my divisional application Serial No. 96,228, filed May 31, 1949, for Chair.

There has thus been provided by the present invention a novel posture chair construction which embodies a number of advantageous features all of which materially contribute to the comfort of the user. The various adjustments which have been provided, enable the chair to be quickly adapted to any individual, it being emphasized that the combined adjustment of back rest position and seat position achieves a variation in the depth of the seat while maintaining the stability of the chair. The floating back rest presents a highly desirable feature and greatly adds to the comfort of the user in the complete elimination of "back rub" when the user leans back in the chair.

While the invention has been shown and described herein with considerable particularity, it will be understood by those skilled in the art, that various changes and modifications thereof may be resorted to without departing from the spirit of the invention. Reference will therefore be had to the appended claims for a definition of the limits of the invention.

What is claimed is:

1. A chair comprising a base, a seat, means for adjustably supporting the seat on the base for substantially horizontal movement with respect thereto, a back rest, and means including a part operatively connecting the base, seat and back rest for adjusting said back rest in opposite directions in a substantially horizontal plane with respect to the seat and for simultaneously adjusting said seat with respect to the base in directions opposite to the movements of the back rest with respect to the seat.

2. A chair comprising a base, a seat, means for adjustably supporting the seat on the base for substantially horizontal movement with respect thereto, a back rest, a support for the back rest, means for adjustably mounting said support on the seat, and means connecting the support, the seat and the base, for moving the seat in a direction opposite to the movement of the support when the latter is moved to adjust the position of the back rest.

3. A chair comprising a base, a seat, means for adjustably supporting the seat on the base for substantially horizontal movement with respect thereto, a back rest, an L-shaped angle iron having one part supporting the back rest and the other part slidably mounted beneath the seat so that the back rest may be adjusted toward and away from the seat, and means interconnecting said other part, the seat and the base for moving the seat in a direction opposite to the direction of movement of said other part.

4. In a chair having a base, a seat and a back rest, means for slidably mounting the seat on the base, means for slidably mounting the back rest on the seat, and means interconnecting the second means, the base and the seat for moving the latter in a direction opposite to the movement of the second means.

5. In a chair having a base, a seat and a back rest, means for slidably mounting the seat on the base, means for slidably mounting the back rest on the seat, and means including a single lever interconnecting the second means, the base and the seat for moving the latter in a direction opposite to the movement of the second means.

6. In a chair having a base, a seat and a back rest, means for slidably mounting the seat on the base, means for slidably mounting the back rest on the seat, and means including a single lever pivotally mounted on the base and having its opposite ends connected respectively to the seat and the second means for moving the seat in a direction opposite to the movement of the second means.

7. A chair comprising a base, a seat spider carried by the base, a seat, means for slidably mounting the seat on said spider so that the seat may move forwardly and rearwardly with respect to the base and spider, a back rest, a support having one part connected to the back rest and a second part slidably carried by the seat so that the support and back rest may move in and out with respect to the base, and means interconnecting the second part, the seat and the spider for moving the seat forwardly as the second part is moved rearwardly, and for moving the seat rearwardly as the second part is moved forwardly.

8. A chair as defined in claim 7 wherein the interconnecting means comprises a lever pivotally mounted between its ends to the spider and having its opposite ends pivotally connected with the second part and the seat respectively.

5 9. A chair comprising a base, a pedestal, a seat spider carried by the pedestal, said spider being provided with a plurality of outwardly extending arms, a seat, means comprising a plurality of tracks carried by the seat for slidably mounting the seat on said arms, so that the seat may be moved forwardly and rearwardly with respect to the spider to adjust the center of the seat with respect to the pedestal, a back rest, means supporting the back rest and slidably mounted beneath the seat, and means interconnecting the supporting means, the spider and the seat for moving the latter in opposite directions with respect to the direction of movement of the supporting means.

10 10. A chair comprising a base, a pedestal, a seat spider carried by the pedestal, said spider being provided with a plurality of outwardly extending arms, a seat, means comprising a plurality of tracks carried by the seat for slidably mounting the seat on said arms, so that the seat may be moved forwardly and rearwardly with respect to the spider, to adjust the center of the seat with respect to the pedestal, a back rest, an L-shaped bracket supporting the back rest and having a part slidably carried by the base so that the back rest may be adjusted with respect to the seat, and a lever connection between said part, the seat and the spider for moving the seat forwardly when said part is moved rearwardly, and for moving the seat rearwardly when said part is moved forwardly.

15 11. A chair comprising a base, a seat adjustably mounted on the base for forward and rearward movement with respect thereto, a back rest, a support for said back rest, means for adjustably mounting said support on said base so that the support may be moved toward and away from the seat, and means interconnecting the support, seat and base for moving the seat forwardly of the base upon movement of the support away from the seat and for moving the seat rearwardly of the base upon movement of the support toward the seat.
